New York, N. Y., a corporation of Virginia

Application March 18, 1932, Serial No. 599,720

5 Claims. (Cl. 242—64)

This invention relates to the supporting of web rolls for supplying printing presses with webs, although it is capable of use in other analogous arts.

5 The principal object of the invention is to provide practical means for moving the individual supporting means for a new web roll into position to pick up the new web roll without moving the rest of the supporting means which carries 10 the running roll.

Other objects and advantages of the invention will appear hereinafter.

Reference is to be had to the accompanying drawings, in which

15 Fig. 1 is an end view of a rotatable reel for carrying web rolls constructed in accordance with this invention, and

Fig. 2 is an elevation of the same.

The ordinary practice in supplying web rolls 20 to printing presses is to bring the new roll into position on a dolly or small truck and to jog the reel back and forth until the arms which are to carry the new roll, or rather the centers for supporting the new roll, coincide with the center of the roll on the truck. This jogging of the reel back and forth is done necessarily, in the most up-to-date practice, while the paper is being fed at full speed from another roll carried by the same reel. It is a well-known fact that the jerking 25 of the running web roll is apt to result in the breaking of the paper being fed therefrom.

The purpose of this invention is to provide means whereby the running roll can be maintained on a stationary axis while a part of the reel is moved back and forth for the purpose of centering it with respect to a new roll. The invention is shown as applied to a rotary reel which is ordinarily used for this purpose but is capable of application to an oscillating support for the 30 rolls as well.

As in ordinary practice, a pair of pedestals 10 carry a shaft 11 which is rotated through a worm wheel 12 from a motor or other source of power, not shown. In this case, the shaft is provided 35 with two hubs 13, adjustably secured to it usually, to provide mountings for the several pairs of arms 14 which are pivotally mounted on the hubs on shafts 15 and constitute pivoted frames for carrying one roll apiece. On one of these hubs 40 are mounted motors 16 equal in number to the number of frames 14. These are reversible motors connected up so as to be operated in either direction controlled by push-buttons at will. Through suitable gearing, they drive worms 17, 45 which in turn drive worm wheels 18 on respective

shafts 19. Each shaft is provided with a pinion 20 meshing with a gear segment 21 which is made integral with each one of the arms 14.

Three pairs of arms are indicated, located at opposite ends of the device and the arms are provided with centers which support the spindles of the web rolls. In the case shown, one spindle is supporting the running web roll R, there is a spare roll R' which has previously been loaded on the reel, and a roll R² is shown on a truck 60 22 in position to be loaded. For the reasons stated, it is not desired to shift the position of the running roll R while this new roll R² is being loaded on the reel. Consequently the motor 16, 65 which corresponds with the pair of arms 14, 70 which are to be used to support the roll R², is set in motion for the purpose of shifting this frame 14 through the gearing described. That pair of arms 14 is moved into position so that the centers carried thereby will coincide with the axis of the roll R². This position is indicated in dotted lines 75 in Fig. 1.

Having brought this pair of arms into registration with the center of the roll, the proper action is taken to mount the roll thereon and 80 then the motor is turned in the opposite direction to bring the arms 14 out into a radial full line position, as it is intended that all of these arms shall be located radially when in operation. The worm 17 of course prevents the arms from 85 being moved out of radial position after once being moved into it, except by the operation of the motor. This construction can be used also to adjust the position of the arms at any time if they do not happen to be in the right position.

In this way it will be seen that the new roll can be picked up without disturbing the position of the running roll, thus avoiding all paper breaks heretofore caused by the operation of moving the whole reel back and forth.

90 Although I have illustrated and described only one form of the invention, I am aware of the fact that modifications can be made therein by any person skilled in the art without departing from the scope of the invention as expressed in the 100 claims. Therefore, I do not wish to be limited to all the details of construction herein shown and described, but what I do claim is:—

1. In a movable support for a plurality of web rolls, the combination of a plurality of pairs of 105 arms, each arm having means for centering and supporting one end of a web roll, said arms being movably mounted on said movable support, and means carried by said support for moving each pair of arms individually for the purpose of 110

cating them in position to pick up a new web roll.

2. In a reel for supporting web rolls, the combination of a central supporting shaft and a plurality of pairs of arms projecting therefrom, each pair having means for supporting a web roll between them and each pair of arms being pivoted on pivots parallel with the axis of the shaft, and means for turning each pair of arms individually as needed into position to pick up a web roll so as to be carried by said reel.

3. In a reel for supporting web rolls, the combination with a rotatable shaft, a pair of hubs mounted on said shaft near its opposite ends, a plurality of shafts parallel with the first shaft and carried by said hubs, an arm carried on each of the last named shafts and constituting a frame for carrying a web roll, and means mounted on the hubs for turning any one of the last-named shafts on its own axis for operating the arms, for the purpose described.

4. In a reel for supporting web rolls, the combination of a rotatable shaft, a pair of hubs fixed thereto, a plurality of frames for supporting web rolls pivoted on said hubs, a series of motors carried by one of the hubs, and means operated by each motor for turning one of said frames on its pivots, for the purpose described.

5. In a reel for carrying web rolls, the combination of a central shaft, a pair of hubs carried by the shaft, a plurality of frames pivoted on said hubs, each frame adapted to carry a web roll, two segmental gears on each frame, a series of motors carried by one of the hubs, a pinion meshing with each of said segmental gears, and means operated by each of said motors for rotating two of said pinions for the purpose of turning a frame on its axis.
